[57] CLAIM

The ornamental design for a portable air freshener container, as shown and described.

DESCRIPTION

FIG. 1 is a top, side perspective view of a portable air freshener container, showing my new design;
FIG. 2 is an enlarged top plan view thereof;
FIG. 3 is an enlarged side elevation view thereof, the other three sides being identical to that shown; and,
FIG. 4 is an enlarged bottom plan view thereof.

FIG. 1

FIG. 4

FIG. 2

FIG. 3
